UNITED STATES PATENT OFFICE.

JULES JUNKER, OF PHILADELPHIA, PENNSYLVANIA.

BAKING-OVEN.

SPECIFICATION forming part of Letters Patent No. 395,979, dated January 8, 1889.

Application filed September 18, 1888, Serial No. 285,669. (No model.)

To all whom it may concern:

Be it known that I, JULES JUNKER, of Philadelphia, in the county of Philadelphia and State of Pennsylvania, have invented a new 5 and useful Improvement in Baking-Ovens, which improvement is fully set forth in the following specification.

This invention has reference generally to baking-ovens, and more particularly to ovens 10 designed to be used for baking cake; and its object is to increase the capacity of the oven and to permit the simultaneous baking of articles requiring different degrees of heat.

Certain cakes—such as “lady-fingers,” for 15 example—must bake rapidly and should not ordinarily remain in the oven more than five minutes, whereas such articles as cinnamon buns must bake slowly, requiring more than an hour to bake them thoroughly. Moreover, 20 goods which are sweet take color rapidly and in an oven which is too hot become black on the outside, and hence unsalable, before they are thoroughly baked. On the other hand, goods having little sugar, but rich in lard, take 25 color slowly and require a hot oven in baking. The product of an oven as ordinarily constructed, when used to bake various articles differing so widely in the respects above pointed out, is necessarily restricted.

According to the present invention an additional sole is built upon the thin crown of 30 an oven, and a small door is constructed above this sole just over the usual oven-door. This additional sole lies in the upper part of 35 the smoke-box, just under the thick crown, and extends from end to end of the oven, but preferably only across half its width. Goods placed upon this additional sole will, on account of the higher temperature, take more 40 color and bake quicker than goods placed in the oven beneath.

In the accompanying drawings, which form 45 part of this specification, Figure I is a central longitudinal section of an oven constructed in accordance with the invention. Fig. II is a transverse section thereof. Fig. III is a horizontal section; and Fig. IV, a transverse section on line $x-x$, Fig. III.

A represents the thin crown, B the sole, D the thick crown, and F the oven-door, all of 50 which are or may be of ordinary construction. The crown A is, however, somewhat higher than in ordinary bread-ovens. Above crown A is laid an additional sole, C, extending the full length of the oven, but only about half- 55 way across the same. The two lateral walls T of the sole are, say, nine inches thick, and between them the usual fire-brick tiles are laid in a bed of concrete, G, which may consist of broken fire-brick and fire-mortar. 60 Over the usual oven-door, F, is the low door, E, for giving access to the space above sole C.

H H, Figs. III and IV, represent the fire-places, and I I are flues for the passage of the 65 hot products of combustion to the space below the sole B. The smoke and gases pass between the sole C and crown D, downward through flues I under the sole B, and thence they pass around a check-plate, K, and escape by a suitable chimney. 70

It is found in practice that an oven constructed as above described permits the simultaneous baking of goods requiring a very hot oven and goods requiring a moderate degree of heat with excellent results. 75

I claim—

1. A baking-oven provided with an additional sole laid upon the thin crown of the oven, and with a door for giving access to the space above said sole, substantially as described. 80

2. In a baking-oven, the combination, with the sole, thin crown, and thick crown, of an additional sole laid upon the thin crown, forming a baking-chamber between it and the 85 thick crown, said sole extending the full length of the oven and about half-way across the same, and a door opening into the space above said sole, substantially as described.

In testimony whereof I have signed this 90 specification in the presence of two subscribing witnesses.

JULES JUNKER.
